UNITED STATES PATENT OFFICE.

GEORGE REDFORD AND EDWIN CAMPBELL, OF SUSSEX, WISCONSIN.

WRENCH.

SPECIFICATION forming part of Letters Patent No. 642,155, dated January 30, 1900.

Application filed September 5, 1899. Serial No. 729,419. (No model.)

To all whom it may concern:

Be it known that we, GEORGE REDFORD and EDWIN CAMPBELL, citizens of the United States, residing at Sussex, in the county of 5 Waukesha and State of Wisconsin, have invented new and useful Improvements in Adjustable Wrenches, of which the following is a specification.

Our invention relates to improvements in 10 adjustable wrenches; and it pertains to a device for locking the movable jaw of the wrench at any desired point of adjustment.

The construction of our device is explained 15 by reference to the accompanying drawings, in which—

Figure 1 represents a side view thereof with part broken away to show the interior construction. Fig. 2 is a cross-section drawn on line $x-x$, and Fig. 3 is a cross-section drawn 20 on line $y-y$ of Fig. 1.

Like parts are referred to by the same reference-letters throughout the several views.

A represents the handle.

B is the shank; C, the stationary jaw, which 25 jaw is rigidly secured to the shank B.

D is the adjustable jaw, which is loosely fitted to the shank B, upon which it is adapted to be moved and adjusted. The jaw D is locked at the desired point of adjustment on 30 the shank by the screw E. The screw E is supported at one end at a fixed point from the shank B by the bracket F and at its opposite end in a screw-threaded bearing G, formed therefor in the movable jaw D. The 35 bearings of the screw E and the pitch of the screw-thread are such as to permit the screw when not locked to be turned freely in either direction by the action of the screw-threaded bearing G and by the movement of the jaw 40 D as it is being adjusted. When the jaw D has been moved to the desired point of adjustment, it is rigidly locked at such point by locking the screw E. It is obvious that the screw E may be locked and prevented from 45 turning in a great variety of ways; but as a preferable form of locking device we employ a beveled pinion or collar H, which is rigidly secured to the screw and normally retained in contact with the bracket F by the bearing- 50 spring J. The bearing-surface of the bracket F is beveled to conform to the beveled surface of the pinion, and the contiguous sur-

faces of both are provided with teeth or corrugations I, which interlock together and prevent the screw E from turning. The pinion H is driven back and held normally in contact with the bracket F by the recoil of the spring J, which is interposed between the bracket and sliding lock. The sliding lock K is swiveled to the protruding end of the 60 screw E by the retaining-pin L. Thus the block K serves as a bearing for the hand of the operator, by which the screw E and pinion H may be moved forward and the pinion H thrown out of engagement with the inclosing bracket. Thus it is obvious that when desired to adjust the movable jaw in either direction it is necessary simply to press against the block K, whereby the pinion will be disengaged from the bracket, when the 70 screw E will be free to turn, thus permitting the jaw to be moved freely in either direction. When the jaw has been adjusted, it is automatically locked by the recoil of the spring J acting against the sliding block K 75 as such block is released from pressure. To prevent the block K from turning with the screw as the jaw is being adjusted, its lower edge is brought in contact with the base of the bracket F.

Having thus described our invention, what we claim as new, and desire to secure by Letters Patent, is—

1. In a wrench, the combination with a movable jaw and a supporting-shank; of an 85 adjusting-screw having threaded bearings in the bearings of the movable jaw, the pitch of the thread of said screw and the bearings, being such as to cause said screw to be turned by the longitudinal movement of said jaw; 90 and means for locking said screw and jaw at the desired point of adjustment.

2. In a wrench, the combination with a movable jaw and a supporting-shank; of an 95 adjusting-screw having threaded bearings in the bearings of the movable jaw, the pitch of the thread of said screw and the bearing being such as to cause said screw to be turned by the longitudinal movement of said jaw; and means for locking said screw and jaw at 100 the desired point of adjustment, consisting of a stationary bracket F; pinion H having bearings in said bracket; bearing-block K swiveled to one end of said adjusting-screw; and

spiral spring or elastic bearing J interposed between said stationary bracket and said block, adapted when released from pressure to hold said pinion in contact with said bracket, all substantially as and for the purpose specified.

In witness whereof we have hereunto set

our hands and affixed our seals this 28th day of August, 1899.

GEORGE REDFORD. [L. S.]
EDWIN CAMPBELL. [L. S.]
